UNITED STATES PATENT OFFICE

HARRY E. BAILEY, OF ALBANY, NEW YORK.

AIR-COMPRESSOR.

No. 904,294.

Specification of Letters Patent.

Patented Nov. 17, 1908.

Application filed June 6, 1908. Serial No. 437,095.

To all whom it may concern:

Be it known that I, HARRY E. BAILEY, a citizen of the United States, and a resident of Albany, in the county of Albany and State of New York, have invented a new and Improved Air-Compressor, of which the following is a full, clear, and exact description.

The invention relates to hydraulic air compressors employed for supplying air pressure to kegs, barrels or other receptacles containing beer and other liquids to be elevated to a dispensing faucet or the like.

The object of the invention is to provide a new and improved air compressor which is simple and durable in construction, not liable to leak or to get out of order, and arranged to prevent the water from accidentally passing into the receptacle filled with beer or other liquid.

20 The invention consists of novel features and parts and combinations of the same, which will be more fully described herein-after and then pointed out in the claims.

A practical embodiment of the invention 25 is represented in the accompanying drawings forming a part of this specification, in which similar characters of reference indicate corresponding parts in all the views.

Figure 1 is a sectional side elevation of 30 the improvement; Fig. 2 is a plan view of the same, the casing body being removed and parts being in section; Fig. 3 is an enlarged sectional side elevation of the improvement showing the parts in a different position 35 from the one shown in Fig. 1; and Fig. 4 is an enlarged transverse section of the same on the line 4-4 of Fig. 3.

The casing A is provided at its bottom with a water inlet B connected with a street 40 main or other suitable source of water supply, and in the water inlet pipe B is arranged a reducing valve C of the usual construction. The water inlet pipe B terminates within the casing A on an upright, 45 slightly tapering valve seat D (see Fig. 4), adapted to be engaged by a disk valve E having a tapering face, and provided with a stem E' slideable in one end of a lever F fulcrumed at F' on a bracket G attached to the 50 bottom of the casing A, as plainly shown in the drawings. The end of the valve stem E' is engaged by a set screw E² screwing in the lever F, to permit the operator to adjust the face of the disk valve E relative to the face 55 of the valve seat D to insure accurate seating of the disk valve E on the seat D, to prevent

water from passing into the casing A at the time the disk valve E is seated on the valve seat D. The lever F carries another disk valve H adapted to be seated on a horizontally-arranged valve seat H' leading to the water discharge pipe H² for carrying the water to a suitable place of discharge. Now by the arrangement described, the valve seats D and H' stand approximately at a right angle one to the other, and when the casing A is emptied the disk valve E is opened while the disk valve H is closed, as shown in Figs. 1 and 3, and when the casing A has filled with water and a swinging motion is given to the lever F, as hereinafter more fully explained, then the valve H swings into an open position while the valve E moves into a closed position on the valve seat D, to shut off the water from the casing A. When the valve H is opened the water flows out of the casing by way of the valve seat H' and the water outlet H².

In order to impart a swinging motion to the valve lever F the following arrangement 80 is made: On the valve lever F is formed an arm F² adapted to be alternately engaged on opposite sides by the free ends of arms I', I² held on a lever I, fulcrumed at I³ on the bracket G. The lever I is provided 85 with a weight I⁴ and with a transversely-extending cam I⁵ adapted to be alternately engaged on opposite sides by friction rollers J', J² held on a float lever J fulcrumed at J³ on the bracket G and provided with a 90 float J⁴ rising and falling with the water in the casing A.

The cam I⁵ of the weighted lever I is provided with an extension I⁶ (see Figs. 2 and 4), adapted to engage a rod K' depending 95 from a valve lever K fulcrumed at K² on the air supply pipe L attached to the bottom of the casing A and extending therein nearly to the top thereof, the lower outer end of the air inlet pipe L having a contracted entrance 100 L' through which passes the air into the pipe L and from the latter into the casing A at the time the water recedes therein. The valve K³ on the valve lever K is preferably in the form of a screw screwing in the lever 105 K and adapted to be seated on the top or upper end of the air inlet pipe L. An air outlet pipe N leads from the top of the casing A, and on its entrance end is arranged a cage O containing a float valve 110 P adapted to rise only to close the air outlet N in case the water should accidentally rise

in the casing A to the top thereof, so that the water is prevented from passing through the air outlet N to the receptacle containing the liquid to be elevated, it being understood that the air outlet N is connected with the said receptacle in the usual manner.

The operation is as follows: When the several parts are in the position shown in Fig. 1, the float J⁴ is in a lowermost position, and the valve E is opened while the valves H and K³ are closed. Water can now enter the casing A through the water inlet B and open valve seat D to fill the casing, the water in rising within the casing causing the float J⁴ to rise, and the friction roller J' finally engages with the cam I⁵, so as to impart a swinging motion to the weighted lever I in the direction of the arrow a'. The weight I⁴ of the lever I finally passes a central position and in doing so it suddenly swings into a lowermost position to the left, whereby the arm I² engages and pushes the arm F² from the left to the right, thus imparting a swinging motion to the lever F to open the valve H and to close the valve E. The water in rising in the casing A, as above described, compresses the air therein and forces the air through the outlet N into the receptacle or other place in which the air pressure is wanted. The weighted lever I in swinging over into the left-hand position causes the opening of the air inlet pipe L by the action of the cam I⁵ on the arm K' (see dotted lines in Fig. 3), so that air can now pass into the casing A by way of the pipe L, while return flow of the air by way of the pipe N is prevented by a suitable check valve (not shown). When the valve H swings open and the valve E is moved into a closed position then the flow of the water into the casing is cut off while the water within the casing can flow through the water outlet H² to a suitable place of discharge. The float J⁴ descends with the falling water within the casing A, so that the friction roller J² finally engages the cam I⁵ and imparts a return swinging motion to the lever I in the inverse direction of the arrow a'. When the weight I⁴ of the lever I now passes a central position at the time the float J⁴ is in a lowermost position and the water has escaped from the casing A, then the lever I suddenly swings downward into a right-hand side position, thus causing the arm I' to act on the arm F² with a view to impart a swinging motion to the lever F, thereby moving the disk valve H into a closed position and the valve E into an open position; at the same time the valve lever K swings back into a closed position to close the upper end of the air inlet pipe L. The above-described operation is again repeated, that is, water again enters the casing A by way of the water inlet B and the valve seat D, to compress the air contained in the cas-

ing A and to discharge the compressed air by way of the air outlet N, and when the water has reached a predetermined level, the weight I⁴ of the lever I has passed a central position, thus causing the swinging over of the lever I into a left-hand position, to again change the position of the lever F carrying the disk valves E and H.

From the foregoing it will be seen that the operator is enabled to accurately adjust the disk valve E, so as to bring the faces of the valve E and the valve seat D in firm contact with each other at the time the valve E moves into a closed position, so that water may not pass into the casing A during the time the valve H is open and consequently water is not wasted.

By providing the pipe L with the contracted inlet end L' dust and other impurities are prevented from passing into the casing A, thus avoiding clogging up of the mechanism arranged within the casing, and by having the cage O and the valve P, water is prevented from passing into the air outlet pipe N in case the water should accidentally rise in the casing A beyond its predetermined level.

Having thus described my invention, I claim as new and desire to secure by Letters Patent:—

1. A hydraulic air compressor, comprising a casing having an inlet and an outlet for the water and an inlet and an outlet for the air, a valve lever a disk valve fixed to said valve lever for opening and closing the said water outlet, and a second disk valve for closing and opening the water inlet and having a stem adjustable in the valve lever, the faces of the said disk valves lying in planes at a right angle one to the other, and the disk valve for the water inlet having a sliding engagement with its seat, a weighted lever for actuating the said valve lever, and a float-controlled mechanism for actuating the said weighted lever.

2. A hydraulic air compressor provided with a water inlet, a water outlet, a vertically-disposed valve seat leading to the said water inlet, a horizontally - disposed valve seat for the said water outlet, a valve lever mounted to swing and having a fixed disk valve for opening and closing the said horizontally disposed valve seat, a second disk valve for opening and closing the vertically disposed valve seat, the said valve being adjustably carried by the valve lever, and means for actuating the said valve lever.

3. A hydraulic air compressor provided with a water inlet, a water outlet, a vertically-disposed valve seat leading to the said water inlet, a horizontally - disposed valve seat for the said water outlet, a valve lever, disk valves held on the said valve lever for opening and closing the said valve seats, the valve for the water outlet being fixed to said

valve lever, and the valve for the water inlet having a stem slideable in one end of said valve lever, means for adjusting the said disk valve for the water inlet, and means for actuating the said valve lever.

4. A hydraulic air compressor provided with a water inlet, a water outlet, a vertically-disposed valve seat leading to the said water inlet, a horizontally-disposed valve seat for the said water outlet, a valve lever, a disk valve fixed on the said lever and adapted to engage the said valve seat for the water outlet, a second disk valve engaging the said valve seat for the water inlet and having a stem slideable on the said valve lever, a set screw screwing in the said valve lever against the end of the said valve stem to adjust the said disk valve for the water inlet, and means for actuating the said valve lever.
5. A hydraulic air compressor comprising a casing having an inlet and an outlet for the water, and an inlet and an outlet for the air, a valve lever carrying disk valves, one for opening and closing the said water inlet and one for opening and closing the said water outlet, the faces of the said disk valves lying in planes at a right angle one to the other, and the disk valve for the water inlet having a sliding engagement with its seat, a weighted lever for actuating the said valve lever and provided with an arm, a valve controlling the said air inlet and actuated by the said arm, and a float-controlled mechanism for actuating the said weighted lever.
6. A hydraulic air compressor comprising a casing having an inlet and an outlet for the

water, and an inlet and an outlet for the air, a valve lever mounted to swing, an adjustable disk valve carried by said lever for opening and closing the said water inlet, a disk valve fixed to said lever for opening and closing the said water outlet, the faces of the said disk valves lying in planes at a right angle one to the other and the disk valve for the water inlet having a sliding engagement with its seat, a weighted lever for actuating the said valve lever and provided with an arm, a valve controlling the said air inlet and actuated by the said arm, a cage at the entrance to the said air outlet, a float valve in the said cage and adapted to close the air outlet when lifted by rising water in the casing, and a float-controlled mechanism for actuating the said weighted lever.

7. A hydraulic air compressor comprising a casing having a water inlet, a water outlet, an air supply pipe for the casing having a contracted inlet end, the said pipe having its discharge end within the casing, a valve lever fulcrumed on the discharge end of the air supply pipe, a screw valve screwing in said lever and adapted to be seated on the discharge end of the air supply pipe, and an air outlet leading from the casing.

In testimony whereof I have signed my name to this specification in the presence of two subscribing witnesses.
